UNITED STATES PATENT OFFICE.

CHARLES F. DAMM, OF BUFFALO, NEW YORK.

HEADLIGHT.

Application filed December 8, 1921. Serial No. 520,946.

To all whom it may concern:

Be it known that I, CHARLES F. DAMM, a citizen of the United States, residing in Buffalo, in the county of Erie and State of New York, have invented new and useful Improvements in Headlights, of which the following is a specification.

This invention relates to a headlight which is more particularly intended for use in automobiles for illuminating the roadway ahead of the same and has for its objects to so construct the lens system of the headlight that a better illumination of the roadway is secured without the usual objectionable glaring effect and also to provide the headlight with side lenses which will give a warning signal toward opposite sides of the car when the latter is about to be turned either way or when crossing the road in front of another car, thereby promoting safety in vehicle travel and reducing the possibility of accidents.

In the accompanying drawings:

Figure 1 is a vertical longitudinal section of one form of headlight embodying my improvement. Figure 2 is a similar view of the frame for holding the front lenses in place on the casing of the headlight. Figure 3 is a front elevation of the headlight shown in Fig. 1. Figure 4 is a fragmentary longitudinal section, on an enlarged scale, taken on line 4-4, Fig. 1, showing the means for supporting a front lens on the casing. Figures 5 and 6 are vertical cross sections on lines 5-5, and 6-6, Fig. 1, respectively, looking in the direction of the arrows associated with these lines. Figure 7 is a front elevation of the front lenses and the frame for holding the same in a developed presentation. Figure 8 is a fragmentary vertical longitudinal section of the front part of the hood shown in Figs. 1, 3, 5 and 6. Figure 9 is a vertical longitudinal section of a headlight showing a modified form of my invention.

Similar characters of reference indicate like parts in the several views.

10 represents the reflector of the headlight which may be of usual parabolic or other suitable form and provided centrally in the back thereof with a socket 11 for receiving the lamp of the headlight which in this instance is of the incandescent bulb type.

Surrounding this reflector is an enclosing

casing or shell which in the construction shown in Fig. 1 comprises a rear section or body 13 which may be of spherical form and receives the reflector 10, and a front section or hood 14 which forms a forward tubular extension from the front edge of the body and in this instance is formed integrally of sheet metal therewith. In the preferred construction the lower portion 15 of the front edge of this hood inclines from its front end rearwardly and downwardly while the upper part 16 of this edge inclines rearwardly and upwardly from the front end of the hood, as shown in Fig. 8. The junction or place of meeting of the front ends of the lower and upper edge portions 15 and 16 is preferably located slightly above the horizontal longitudinal axis of the reflector and casing on which the illuminating lamp is located and the angle of the lower front edge portion 15 is inclined at a comparatively low angle while the upper edge portion 16 is inclined at a relatively high angle so that the lower edge portion is longer in a direction fore and aft and extends back farther than the upper edge portion 16 of the hood, as shown in Fig. 8.

Arranged across the lower part of the hood adjacent to the lower edge portion 15 thereof is a lower lens or pane 17 which is arranged at the same angle as this edge and is of substantially the same length fore and aft of the headlight, and arranged across the upper part of the hood adjacent to the upper edge portion 16 thereof is an upper lens or pane 18 which stands at the same angle as this last-mentioned edge portion and extends fore and aft of the hood to substantially the same extent, so that the lower front lens is inclined at a comparatively low angle and is comparatively long and extends back farther than the upper lens which latter is inclined at a relatively high angle and is somewhat shorter than the lower lens, by reason of the fact that the same does not extend back so far.

Any suitable means may be provided for holding these front lenses in position on the front part of the hood, those shown in the drawings being preferred and constructed as follows:

19 and 20 represent the lower and upper sections of a fastening frame or rim which are preferably constructed integrally of sheet metal, the lower section 19 being

adapted to fit around the lower part of the front edge portion 15 of the hood at the same angle thereof and bearing against the front side of the lower lens 17, while the 5 upper section 20 is adapted to fit around the upper part of the hood adjacent to the front edge portion 16 thereof at the same angle as the latter and bear against the front side of the upper lens 18. This frame 10 may be connected with the hood in any suitable manner preferably by means of screws 21 which permit of detaching the frame from the hood and attaching the same thereto when this is required for replacing 15 a broken lens. At the angle between the meeting ends of the lower and upper sections of the frame is a cross bar 22 extending horizontally and transversely across the same so as to cover the joint or meeting 20 place between the lower edge of the upper lens 18 and the upper edge of the lower lens 17. Projecting downwardly from the central part of this cross bar is a shield 23 which is arranged horizontally in line with 25 the lamp 12 and thus intercepts the rays of light which are thrown horizontally forward by this lamp and thereby prevents a glaring effect of the same upon the roadway ahead. This fastening frame for supporting or retaining the front lenses is preferably constructed from a single piece of sheet metal, the lower and upper sections and the cross bar of which are preferably made of hollow form for the purpose of 30 stiffening the same and also permitting of fitting the same around the hood and engaging the front sides of these lenses.

Although any suitable means may be employed for detachably holding the lenses 40 against the rear sides of the frame sections, those which are shown in the drawings are suitable and comprise upper and lower lens retainers 24, 25, which are constructed of spring wire, the upper retainer 24 being arranged between the rear side of the upper lens 18 and a plurality of clips 26 arranged on the upper section 20 of the frame while the lower retainer 25 is arranged between the rear side of the lower lens 17 and a plurality 50 of retaining clips 27 arranged on the inner side of the lower frame section 19, as best shown in Figs. 1, 4 and 5.

The upper lens 18 is preferably made translucent by constructing the same, for 55 example, of ground glass, while the lower lens 17 is made fully transparent by making the same of clear glass. By this means the light penetrating the upper translucent lens will be subdued and prevented from 60 producing a glare or blinding effect upon the eyes of oncoming persons, while the light of the lamp is free to pass through the clear glass of the lower lens and fully illuminate the roadway in front and at the 65 side of the path of the automobile.

By arranging the upper and lower lenses at an angle relatively to each other, a much larger light opening in a forward direction from the reflector is obtained than has heretofore been obtained in headlights of the 70 same size of usual construction.

By extending the lower front lens back farther than the upper front lens and at an lower angle than the upper lens, the stream of light passing forwardly from the lamp is 75 not only divided but the upper part utilized to moderately illuminate the road ahead by reason of its passing through the translucent upper lens while the lower part thereof passes downwardly and forwardly 80 through the clear glass lens and fully illuminates the roadway in front of the lamp and at the side thereof. This illumination is, however, effected without blinding the 85 eyes of oncoming persons, inasmuch as the glare of the lamp is kept below the line of vision of oncoming persons by intercepting the upper glaring rays of the lamp through the medium of the translucent upper lens 18, the cross bar 22 and the shield 23.

In order to still further increase the illuminating effect of the roadway in front of the lamp without accompanying the same by a glaring effect, the hood and body of the casing and also the reflector are elongated in a vertical direction so that the same are substantially of oval form, the major axis of which is vertical and the minor axis is horizontal, as shown in Figs. 3, 6 and 7. By this means a greater lighting effect in 100 a vertical direction is obtained from the head light, for a given size headlight, without increasing the cost of the same.

The construction shown in Fig. 1 is more particularly designed for use in headlights 105 which are originally manufactured in accordance with my invention, which permits of making the body and hood of the casing in one piece.

In order to adapt this invention to headlights already in use, the same may be organized, as shown in Fig. 9. For example, the hood 28 is made separate from the body 29 of the casing and is connected therewith by screws 30. In such an organization a separate retaining frame for the front members may be dispensed with and replaced by a frame or rim 31 which is formed integrally on the front edge of the hood 28 and turned inwardly and backwardly so as to engage the front sides of the upper and lower front lenses 32, 33. This integral frame may also be provided with a cross bar 34 to support the front meeting edges of the upper and lower lenses 32, 33 and on its underside this cross bar may also be provided with an integral shield 35 for intercepting the glaring rays of the lamp 12 at the axis of the headlight.

For the purpose of utilizing this headlight 130

as a signal for indicating the direction in which the driver is turning and thus avoid accidents with cars following near by, the opposite upright side walls or parts of the 5 hood are provided with openings 36, 37, across which side lenses or panes 38, 39 are secured by frames or rims 40, or similar means. That side lens next to the side of the car is preferably of a red color and the 10 other of a white or clear color, so that upon turning a car one way or another a signal will be visible to a car approaching from the rear, indicating that the driver is turning across the path of the car following, 15 while the white light on the opposite side of the headlight will illuminate the roadway adjacent thereto and thus increase safety in travel at night.

I claim as my invention:

A headlight comprising a reflector adapted to contain a lamp, a casing having a rear body enclosing said reflector and a hood extending forwardly from said body and having the lower part of its front edge inclined rearwardly and downwardly and the upper 25 part of said edge inclined rearwardly and upwardly, a lower inclined clear lens mounted on the lower inclined edge of said hood, and an upper inclined translucent lens mounted on the upper inclined edge of said hood, said lower lens being longer fore and aft than said upper lens and lenses of different colors arranged on horizontally opposite sides of said hood.

CHARLES F. DAMM.
